(57) **CLAIM**

The ornamental design for an insect deterrent invention, as
shown and described.

DESCRIPTION

FIG. 1 is a perspective view showing our new design of the
insect deterrent design.

FIG. 2 is top plan view of the insect deterrent design of FIG.
1.

FIG. 3 is a front elevation view thereof, the rear elevation view
being substantially the same.

FIG. 4 is a right side elevation view thereof, the left side
elevation view being the same; and,

FIG. 5 is a bottom plan view thereof.
